ERLE J. BYERLEIN, OF WAUWATOSA, WISCONSIN.

METHOD OF AND MACHINE FOR CASTING.

Application filed October 20, 1927. Serial No. 227,526.

This invention relates to improvements in method of and machine for casting.

It is one of the objects of the present invention to provide a method of and machine for casting in which sand or refractory material molds may be used a great number of times in casting similar articles, and thus eliminate considerable expense over the ordinary operation in providing a new sand or refractory material mold for each casting made.

A further object of the invention is to provide a method of and machine for casting in which the sections of the mold are movable away from each other to strip the casting while the casting is momentarily suspended before being discharged.

A further object of the invention is to provide a method of and machine for casting in which the stripping and discharge of the casting is automatic with the separation of the mold sections.

A further object of the invention is to provide a method of and a machine for casting which is of simple construction, is strong and durable and is well adapted for the purpose described.

With the above and other objects in view, the invention consists of the improved method of and machine for casting, and its parts and combinations as set forth in the claims, and all equivalents thereof.

In the accompanying drawings, in which the same reference characters indicate the same parts in all of the views:

Fig. 1 is a top view of the improved casting machine shown in closed or casting position;

Fig. 2 is a side view thereof;

Fig. 3 is a central vertical transverse sectional view taken on line 3—3 of Fig. 1;

Fig. 4 is a central longitudinal sectional view taken on line 4—4 of Fig. 1, showing the mold sections in closed positions;

Fig. 5 is a fragmentary sectional view with the mold section in open position and the casting maintained in a central position therebetween;

Fig. 6 is a sectional detail view of a modified form of stripping pin; and

Fig. 7 is a side view of the operating lever and connected links shown in open position.

Referring to the drawings, the numeral 8 indicates a base member which is provided

with upright standards 9 to which parallel 55 guide bars 10 are connected. Frame members 11 have eyed opposite end portions 12 through which the guide bars 10 extend to permit the said members to slide thereon towards and away from each other. Said 60 frame members are formed with flat face portions 13 to which the flask members 14 are connected by bolts 15. The front sides of the flask members are open. Flasks of any size desired may be bolted to the frame. The 65 opposite sides of each flask are formed with outwardly extending lugs 16, of which the lugs on one flask member are provided with tapered dowel guide pins 17 and the lugs on the other flask member are formed with holes 70 18 to receive the pins and aline the two members when the flask members are adjacent each other, as shown in Figs. 1 to 4 inclusive. The base member 8 is also provided with upwardly extending standards 19 to which are 75 pivotally connected by screws 19' the end portions of a U-shaped lever 20. Said end portions have opposite extensions 21 forming double bell crank levers to which the inner ends of links 22 are pivotally connected by screws 22'. The links are of curved formation, as clearly shown in Fig. 2, and extend in pairs above and below each other, and the outer ends of each pair of links are pivotally connected to the end portions of the 80 23. When the flask members are in closed position, as shown in Figs. 1, 2 and 4, the U-shaped lever 20 is in its lowermost position, and the pivot screws of the U-shaped lever 90 and the links are in alined horizontal position, and which position locks the flask members against movement away from each other. When the flasks are in open position the lever 20 and the connected links 22 are in the position shown in Fig. 7.

Supplemental frame members 24, having eyed end portions 24', are slidably mounted on the guide bars 10 and are yieldingly held in their forward position against collars 25 100 by coiled springs 26. The springs surround the guide bars and are interposed between the eyed end portions of the frame members 9 and the supplemental frame members 24. The collars 25 are adjustably mounted on the guide bars 10 and are held in adjusted position by set bolts 27. Bolts 28 rigidly connected to the medial portions of the supplemental

frames 24 extend outwardly therefrom and loosely through openings 29 in the frames 9, and at their outer ends are provided with nuts 30 to also adjustably control the inward movement of the supplemental frames and permit a close adjustment of the collars. In adjusting, the nuts 30 are turned to properly position the supplemental frames and the collars are then adjusted to the position of the supplemental frames.

The flask members are provided with inwardly extending tubular members 31 to receive stripping and holding pins 32 which at their outer ends are rigidly connected to the supplemental frames 24 and move therewith. The forward portions of the pins extend slidably through the tubular sleeves, and at their inner ends are formed with conical points 32' around which the molten metal is poured in forming castings in the mold flask members. The stripping pins 32 of the opposite supplemental frames are in alinement with each other, and their inner conical ends, when in their innermost position, are spaced apart a distance approximately the thickness of the casting at the points of engagement therewith.

In molding, the flask members are filled with sand or other refractory material 33, and the pattern is placed therein in the ordinary manner to form the mold in each flask member, and when formed, the said members are mounted on the holding members with the pins extending through the tubular members of the flasks and the conical sprue or filling opening or duct 34 extending upwardly. This opening communicates with the mold recesses 35 by branch ducts 36, and each mold recess is provided with an air opening or duct 37 to permit the free escape of the air and hot gases from the mold recesses in casting. The operating lever 20 is then swung downwardly to slide the flask sections together, and when in this position, the conical ends of the stripping pins will just project into the mold recesses, as shown in Fig. 4. In casting wheels, as shown, the stripping pins would enter the axial portions of the mold spaces or any other spaces desired. The molten metal is then poured in the sprue opening to fill the mold recesses, and when the metal has set, the U-shaped lever member is swung upwardly to separate the flask members. The lever member will slide the flask members away from each other until the flask frames contact with the supplemental frames, as indicated in Fig. 5, and in this position the casting or castings will be stripped from the sand and held between the flask members by the stripping pins. A further movement of the lever member will cause the flask frames to move the opposite supplemental frames and the stripping pins away from each other and permit the completed casting or castings to drop. The lever member is then swung to its lower posi-

tion to slide the molding flask members to closed position, and in moving, the springs will move the opposite supplemental frames and stripping pins towards each other to casting engaging position.

Attention is also directed to the fact that when the mold sections are in closed position, the alined position of the pivot screws of the operating lever forms a lock to prevent accidental separation of the flask members. Furthermore, at the start of separation and at the end point of closing of the flask members, the movement is very slow, due to the relative position of the arms of the bell crank lever and the links, so that the refractory material or sand forming the mold is not disturbed.

In the modified form shown in Fig. 6, the end of the stripping rod 32 is provided with a conical or other shaped recess 38 in lieu of conical or other shaped points shown in the first form.

As the flask members are moved towards and away from each other in a straight line without jarring, and the stripping pins hold the casting or castings immovable in mid-position therebetween, there is no tendency to disturb the refractory material or sand of the flasks forming the mold, with the result that the same mold sections may be used for forming castings a great number of times.

Furthermore, if desired, the mold sections may be formed of refractory material of sufficient hardness to be bolted directly to the frame members 11 and thus dispense with the use of the flask members.

From the foregoing description, it will be seen that the method of and machine for molding is very simple and easily carried out, and permits the use of molds a great number of times.

What I claim as my invention is:

1. A casting machine, comprising a support having a guide means, flask sections slidably mounted thereon and movable towards and away from each other, stripping pins extending through the flask sections and into the recesses forming the mold for engaging the casting to be formed therein, means for moving the flask sections to open positions while the stripping pins are in their casting engaging position, and means for moving the stripping pins to casting disengaging position while the flask sections are in open position.

2. A casting machine, comprising a support having spaced guide bars, flask holding frames slidably mounted on the guide bars and movable towards and away from each other, flask sections mounted on the holding frames and movable therewith, a supplemental frame slidably mounted on the guide bars and provided with stripping pins which extend through the flask sections and into the recesses forming the mold for engaging the opposite sides of the casting to be formed

- therein, a lever member for moving the flask sections towards open position a predetermined distance and then moving the stripping pins to casting disengaging position 5 while further moving the flask sections to full open position, and other means for moving the supplemental frames and the stripping pins to casting engaging position.
3. A casting machine, comprising a support 10 having spaced parallel guide bars, flask holding frames slidably mounted on the guide bars and movable towards and away from each other, flask sections mounted on the holding frames and movable therewith, a supplemental frame 15 slidably mounted on the guide bars and provided with stripping pins which extend through the flask sections and into the recesses forming the mold for engaging the opposite sides of the casting to be formed therein, a lever member for moving the flask sections towards open position a predetermined distance and then moving the stripping pins to casting disengaging position while further moving the flask sections 20 to full open position, and spring means for yieldingly moving the supplemental frames and the stripping pins connected thereto towards each other to casting engaging position.
4. A casting machine, comprising a support 25 having spaced parallel guide bars, flask holding frames slidably mounted on the guide bars, flask sections carried by the holding frames, a lever member for moving the holding frames towards and away from each other, supplemental frames mounted on the guide bars in the path of movement of the flask holding frames and moved thereby at the outer end portions of the movements of said holding frames, stripping pins carried 30 by the supplemental frames and extending into the flask sections to casting holding position, stop means for limiting the inward movement of the supplemental frames, and a yielding means holding the supplemental frames against the stop means.
5. A casting machine, comprising a support 35 having spaced parallel guide bars, flask holding frames slidably mounted on the guide bars, flask sections carried by the holding frames, tubular guide members forming part of the flask sections and extending into the sections in the line of movement of the sections, a lever member for moving the holding frames towards and away from each other, supplemental frames mounted on the guide bars in the path of movement of the flask holding frames and moved thereby at the outer end portions of the movements of said holding frames, stripping pins carried by the supplemental frames and extending through the tubular members of the flask sections to casting holding position, stop collars adjustably mounted on the guide bars for limiting 40 the inward movement of the supplemental frames, and coiled springs for yieldingly holding the supplemental frames against the stop collars.
6. A casting machine, comprising a support 45 having spaced parallel guide bars, flask holding frames slidably mounted on the guide bars, flask sections carried by the holding frames and having inwardly extending tubular guide members, a lever member having a linked connection with the holding frames for moving said frames towards and away from each other, supplemental frames slidably mounted on the guide bars and in the path of movement of the outer portions of the holding frames and moved thereby at the outer end portions of the movements of said holding frames, stripping pins carried by the supplemental frames and extending through the tubular guide members of the flask sections to casting holding position, stop collars adjustably mounted on the guide bars for limiting the inward movement of the supplemental frames, and coiled springs surrounding the guide bars and interposed between the support and the supplemental frames for yieldingly holding the supplemental frames against the stop collars.
7. A casting machine, comprising a support 50 having spaced parallel guide bars, flask holding frames slidably mounted on the guide bars, flask sections carried by the holding frames and having inwardly extending tubular guide members, a lever member having a linked connection with the holding frames for moving said frames towards and away from each other, supplemental frames slidably mounted on the guide bars and in the path of movement of the outer portions of the holding frames and moved thereby at the outer end portions of the movements of said holding frames, stripping pins carried by the supplemental frames and extending through the tubular guide members of the flask sections to casting holding position, the inner ends of said stripping pins being of conical form, stop collars adjustably mounted on the guide bars for limiting the inward movement of the supplemental frames, other means for adjustably limiting the inward movement of the supplemental frames, and coiled springs surrounding the guide bars and interposed between the support and the supplemental frames for yieldingly holding the supplemental frames against the stop collars.
8. A casting machine, comprising a support 55 having spaced parallel guide bars, flask holding frames slidably mounted on the guide bars, flask sections carried by the holding frames and having inwardly extending tubular guide members, a lever member having a linked connection with the holding frames for moving said frames towards and away from each other, said link connections locking the holding frames in closed position,

supplemental frames slidably mounted on the guide bars and in the path of movement of the outer portions of the holding frames and moved thereby at the outer end portions 5 of the movements of said holding frames, stripping pins carried by the supplemental frames and extending through the tubular guide members of the flask sections to casting holding position, stop collars adjustably 10 mounted on the guide bars for limiting the inward movement of the supplemental frames, and coiled springs surrounding the guide bars and interposed between the support and the supplemental frames for yieldingly holding the supplemental frames 15 against the stop collars.

9. A casting machine, comprising a support having spaced parallel guide bars, flask holding frames slidably mounted on the guide 20 bars, flask sections carried by the holding frames and having inwardly extending tubular guide members, a lever member having a linked connection with the holding frames for moving said frames towards and away 25 from each other, said link connections having pivotal means which are in locking alignment with each other when the flask sections are in closed position, supplemental frames slidably mounted on the guide bars and in 30 the path of movement of the outer portions of the holding frames and moved thereby at the outer end portions of the movements of said holding frames, stripping pins carried by the supplemental frames and extending 35 through the tubular guide members of the flask sections to casting holding position, stop collars adjustably mounted on the guide bars for limiting the inward movement of the supplemental frames, and coiled

40 springs surrounding the guide bars and interposed between the support and the supplemental frames for yieldingly holding the supplemental frames against the stop collars.

10. A casting machine, comprising flask sections movable towards and away from 45 each other, stripping members positioned to be engaged by the casting to be formed in the mold, means for moving the flask sections away from each other while the stripping members hold the casting, and means for 50 moving the stripping members away from the casting to discharge the casting from the mold.

11. A casting machine, comprising flask sections movable towards and away from 55 each other, stripping members positioned to have their inner end portions engaged by opposite side portions of the casting to be formed in the mold, means for moving the flask sections in a straight line away from 60 each other while the stripping members hold the casting, and means for moving the stripping members in a straight line away from each other and in a line parallel to the movement of the flask members to discharge the 65 casting from the mold.

12. A casting machine, comprising mold sections, one of which is movable towards and away from the other, a stripping means positioned to be engaged by the casting to be 70 formed in the mold, means for moving one of the flask sections away from the other while the stripping members hold the casting, and means for moving one of the stripping members away from the casting to discharge 75 the casting from the mold.

In testimony whereof, I affix my signature.
ERLE J. BYERLEIN.
